M. HANFF

DRILLING HEAD

Filed Oct. 27, 1921

*Inventor
M. Hanff,
By Market Clark
Atty's*

UNITED STATES PATENT OFFICE.

MAX HANFF, OF BERLIN, GERMANY, ASSIGNOR TO THE FIRM ALWIN BERGER, OF BERLIN, GERMANY.

DRILLING HEAD.

Application filed October 27, 1921, Serial No. 510,964, and in Germany February 5, 1921.

This invention relates to drilling heads of the type wherein an angled gear for transmitting the rotary motion, must be provided at a short distance from the tool and consequently drillings, etc., from the work piece being drilled, are liable to get into the inter-engaging parts of the elements of the gear and interfere with the rotational motion.

10 This is particularly the case with dentists' drills comprising an angle head. Notwithstanding the well-made and apparently tight mounting of the drill, millings or drillings from the teeth as well as saliva and the like are very liable to find their way into the closed interior of the casing containing the angled gear.

15 This drawback is greatly intensified by the presence of the lubricating hole which is necessarily provided at the meshing point of the gear and is always open. The fine teeth of the bevel wheels take up the dirt which coagulates during the intervals of rest. The starting again of the drill by the dentist, 20 which experience shows always takes place abruptly, frequently leads to a fracture of the bevel toothed wheels or at least reduces their life and efficiency. It is not feasible for the drill to be repeatedly taken apart by 25 the dentist because the latter has probably not the necessary expert knowledge or time.

30 According to this invention the casings of drill heads are provided with devices such as will allow the dentist, without loss of time, to keep the bevel wheels and their meshing constantly under observation, and also enable the internal parts of the gear to be cleaned and kept free from dirt by means 35 of a convenient and copious supply of benzine or other cleaning liquids as well as by mechanical treatment. The open lubricating hole is dispensed with.

35 Some constructional forms of this invention are illustrated by way of example in the accompanying drawings, in which:

40 Figs. 1 and 2 show an improved head fitted with a flap lid respectively in the closed and open state.

45 Figs. 3 and 4 show the same head with a sliding lid, and

Fig. 5 shows the head taken apart.

Referring to Figs. 1 and 2, *a* is the head with a hinged flap lid. When closed the out-

line of the flap is scarcely visible and does not disturb the dentist in any way. A tight 55 closure is effected in the usual manner by snapping together two filed places, one behind the other. The flap is opened by lifting up with the finger nail at the place *c* prepared for this purpose. 60

In Figs. 3 and 4, the flap is replaced by sliding lid *d*. In this construction it is sufficient for opening the lid to provide a flat knob *e*.

65 In Fig. 5 the casing or head consists of the two parts *a* and *f* which can be connected together for instance by means of small screws *g*. Of course, if desired, all the bearing surfaces may be made tight, preferably and most simply by grinding together to form as wide and smooth surfaces as possible. Instead of being applied to the angled gear as shown, the devices of this invention may, of course, be applied to other heads or casings containing driving wheels 75 or similar parts for transmitting rotary motion through an angled drive. 70

80 What I claim as my invention and desire to secure by United States Letters Patent is:

85 In a dental drill, a drilling head including in combination, a dust proof casing formed of a single piece of rigid material and having the form of an elbow, shafts journalled through the ends of the casing and having the adjacent end portions arranged at right angles and positioned at the bend of the casing, intermeshing gears 90 on the adjacent ends of the shafts and within the casing, the casing being provided with an aperture in one side adjacent the bend thereof and adjacent the point of engagement of the gears to permit of oiling of the gears, the apertures being relatively small so that cleansing and control of the 95 drive is possible while it is impossible to take the drive apart or alter the relative position of the intermeshing teeth of the gears and a removable cover the edges of which are arranged in overlapped engagement with the edges of the aperture for closing the aperture and maintaining the casing dust proof. 100

In testimony whereof I have affixed my signature.

MAX HANFF.
